UNITED STATES PATENT OFFICE.

JOHANNES IHLEFELDT, OF DESSAU, GERMANY.

MULTICHAMBER MILL FOR GRINDING MATERIALS OF ALL KINDS.

Application filed March 4, 1927. Serial No. 172,871.

The invention relates to a multi-chamber mill for grinding materials of all kinds, as for example cement, limestone, coal, carbide and the like. The method of working of the multi-chamber mills in use at present is such, that the balls contacting with the lower portion of the ascending surface of the drum shell are, owing to their centrifugal force, lying upon and pressing it until they will separate from it when having reached a certain height and will fall down in a projectile-like motion on the remaining grinding bodies, or on the drum shell respectively. The material to be ground is broken to pieces by the grinding bodies falling down upon it, the effect being that the pieces are thrown about in all directions and are finally received in hollow spaces between adjacent groups of balls. Now, experience has disclosed the fact that the pieces formed by the striking-down of the balls upon the material, are detrimental to the fineness of the material for the reason that the small pieces, as well as larger ones will find access into the slits of the intermediate plate and from here into the next chamber, without having been ground to the fineness required for this chamber. Besides, this possibility is favored by the fact that the slits and apertures of the individual intermediate walls are distributed more or less equally over the several walls.

My invention obviates the disadvantages inherent to the usual construction by providing segment-shaped apertures extending for some length essentially in proximity to the interior periphery of the drum in such a manner that the aperture in each partition will be staggered with respect to the aperture in the neighbouring partition wall. According to my invention, in addition to this, the apertures are provided with grates which preferably may be made adjustable and exchangeable and in some cases also be provided with lifting shovels.

Also, constructions have been proposed having apertures in the partition walls between the several compartments, said apertures being so arranged that the aperture of one partition wall is staggered with respect to the aperture of the neighbouring partition wall (see for instance French Patent 461,129). This construction, however, has the disadvantage that these apertures are of relatively small width near the periphery and in addition to this extend as far as to

the axis of the drum. This construction furthermore has the disadvantage, that material will pass from one compartment into the neighbouring compartment too closely to the axis of the drum, whereby this material is not sufficiently finely ground when passing into the subsequent compartment of the drum.

The invention is illustrated diagrammatically and by way of example on the accompanying drawing, on which Figure 1 is a longitudinal section through a mill designed according to this invention, and Figures 2, 3, 4 and 5 are details, all as fully described hereinafter.

On the drawing *a*, Fig. 1, denotes the body of the mill; *b* are intermediate walls, the outlet apertures *c* of which are arranged alternately according to this invention. This arrangement of the outlet apertures *c* in the several intermediate walls *b* is rendered possible, for instance, thereby that the apertures are combined in the shape of segments. In Fig. 2 the segment *c* is located in the upper part of the wall. With the next wall the segment *c* lies in the lower part as in Fig. 3. In Fig. 4 the segment is shut up by some grate bars *f*, in order to separate the different kinds of grinding bodies. These bars may be adjustable and (or) exchangeable. Fig. 5 shows how the material to be ground gets into the next following grinding chamber with the aid of shovels *g* directed correspondingly and how it is distributed over the material already present therein, as well as over the balls.

I claim:

1. A multi-chamber mill comprising in combination, a longitudinal rotatory casing, partition walls subdividing said casing into compartments, said partition walls having segment-shaped apertures extending for some length essentially in proximity to the interior periphery of said casing for letting the material pass through from one compartment into the next and so on, the aperture in each of said partition walls being staggered with respect to the aperture in the neighbouring partition wall.

2. A multi-chamber mill comprising in combination, a longitudinal rotatory casing, partition walls subdividing said casing into compartments, said partition walls having segment-shaped apertures extending for some length in proximity to the interior periphery of said casing and adapted to let the

material pass through from one compartment into the next and so on, and grates in said apertures, the aperture in each of said partition walls being staggered with respect to the aperture in the neighbouring partition walls.

3. A multi-chamber mill comprising in combination, a longitudinal rotatory casing, partition walls subdividing said casing into compartments, said partition walls having

apertures adapted to let the material pass through from one compartment into the next and so on, the aperture in each of said partition walls being staggered with respect to the aperture in the neighbouring partition wall, and exchangeable grates provided within said apertures. 15

In testimony whereof I affix my signature.

JOHANNES IHLEFELDT.
